UNITED STATES PATENT OFFICE.

GUSTAV E. HAAR, OF WASHINGTON, DISTRICT OF COLUMBIA, ASSIGNOR OF ONE-HALF
TO JOHN H. STEPHENS, OF VERNON, TEXAS.

PUMP.

1,210,163.

Specification of Letters Patent. Patented Dec. 26, 1916.

Application filed February 25, 1916. Serial No. 80,511.

To all whom it may concern:

Be it known that I, GUSTAV E. HAAR, a citizen of the United States, residing at the city of Washington, in the District of Columbia, have invented certain new and useful Improvements in Pumps, of which the following is a specification.

This invention relates to pumps.

One object is to provide a pump embodying among other characteristics means whereby its piston may be effectively operated by means arranged adjacent its lower end with a minimum amount of power.

Another object resides in the provision of a pump designed to deliver water directly from its casing or to a point above its casing by various sources of power interchangeably connected to the piston of the pump.

A still further object is to provide a pump including a casing on which is mounted a sleeve provided with a projection in which a shaft is mounted for rocking movement and which has connection with the piston of the pump to operate the latter upon rocking movement of the shaft.

With the above and other objects in view, the present invention consists in the combination and arrangement of parts hereinafter more fully described, illustrated in the accompanying drawings, and particularly pointed out in the appended claims, it being understood that changes may be made in the form, size, proportion and minor details without departing from the spirit or sacrificing any of the advantages of the invention.

In the drawings: Figure 1 is a side elevation of one embodiment of the invention. Fig. 2 is a front elevation. Fig. 3 is a horizontal sectional view on the line $a-a$ of Fig. 1. Fig. 4 is a side elevation showing a mechanical motor connected to the pump to operate the same. Fig. 5 is a top plan view of the motor and adjunctive parts.

Referring now more particularly to the accompanying drawings, the reference character 10 indicates the foot piece of my improved pump which may be secured in proper position over a well on a base A' through the instrumentality of suitable fastenings 11 or other suitable means, the base A' having an extension A² for the support of a power transmission mechanism D.

The pump casing A preferably includes

upper and lower sleeves 12 and 13 which are connected at their inner ends by a four-way pipe connection B, the lower sleeve 13 extending through the base 10 and connecting in the usual manner with the usual pump cylinder (not shown). The upper sleeve 12 is closed by a cap 14 provided with a hollow upstanding boss 15 through which the piston rod 16 of the pump may reciprocate.

A water outlet 17 is connected with the four-way pipe connection B in any suitable manner and is provided with a valve 18, while on the opposite side of the four-way pipe connection B a pipe 19 is connected through the instrumentality of a suitable nipple 20 in which a valve 21 is disposed.

A sleeve 22 is mounted on the lower pump casing section 13 prior to the connection of the latter with the four-way pipe connection B and the pump cylinder and is removably secured on said section 13 directly over the base 10 by means of a collar 22' and suitable fastenings 23. This sleeve 22 is in the form of a casting provided with a lateral projection including a horizontal web 24 and a vertical web 25, there being a flange 26 at the outer end of said projection and cooperating with which is a flange 27. The flanges 26 and 27 are formed to provide a bearing to receive the shaft 28 and may be secured operatively together by means of suitable bolts 30 or the like 29.

Keyed on the shaft 28 is a double armed lever C including arms 30 and 30' and whose arm 30 has pivotal connection 31 with a relatively long link 32 which extends along one side of the pump casing. A short arm 33 is keyed to the opposite end of the shaft 28 and has pivotal connection 34 with the lower end of a relatively long link 36 which extends alongside of the pump casing opposite the side along which the link 32 extends. These two links 32 and 36 are detachably connected at their upper ends to a cross-head 37 by means of the removable fastenings a . The cross-head is provided with a yoke 38 from which extends a perforated extension 39 to which a part of a wind-mill mechanism (not shown) may be adjustably connected to operate the pump from a wind-mill, if desired. The cross-head 37 is connected to the piston rod 16 in any suitable manner, one manner of connecting said parts being to provide a nut 40

which may have removable screw threaded connection with the upper end of the piston rod 16.

Keyed on one end of the shaft 28 adjacent 5 the aforesaid double armed lever C is a relatively short arm 41 provided with a longitudinal recess 42, preferably dovetailed in cross section, and in which is removably fitted the lower end of a curved operating handle 43 which may be secured in said recess through the instrumentality of suitable fastenings 44.

To operate the pump to deliver water through the spout 17 it is simply necessary 15 to close the valve 21 and open the valve 18 and reciprocate the handle 43 back and forth straight out from the operator's shoulder, which causes a rocking movement of the shaft 28, and a consequent oscillation of the 20 double armed lever C and the lever 33 which causes vertical reciprocation of the aforesaid links 32 and 33 which, being connected at their upper ends by the cross-head 37, and the latter being connected to the piston rod 25 16, the latter is reciprocated, and the pump is operated to deliver water through the spout 17.

Under certain conditions, it may be desired 30 to operate the pump by a mechanical power transmission mechanism D instead of the manual power hereinbefore described. In this event it is preferred to disconnect the handle 43 from the arm 41, as shown in Fig. 4 and pivotally connect to the arm 30' of the aforesaid double armed lever C, a pitman 45 which is pivotally connected at 46 eccentrically to a gear 47 mounted on a shaft 48 rotatably supported in a suitable frame 49 of the power transmission mechanism D. This 40 gear 47 intermeshes with a pinion 50 secured to a shaft 51 journaled in said frame 49. On the shaft 51 is mounted a gear 52 which intermeshes with a pinion 53 on the shaft 48, on which latter is also secured a 45 pulley 54 to which may be readily connected a belt or the like (not shown) leading from any suitable driving force not shown. Thus, by operating the power transmission mechanism, the piston 16 will be reciprocated in the same manner as when the pump is operated by manual power, with the result that if the valve 21 is closed and the valve 18 open the water may be delivered through the spout 17.

55 If it be desired to lift the water to a tank or the like (not shown), it may be done either by manual reciprocation of the handle 43 or through the instrumentality of the power transmission mechanism D hereinbe-

fore described. In such an event, the valve 60 18 is closed and the valve 21 is opened so that the water may be lifted to the tank through the pipe 19 and its nipple connection 20 with the pump casing, the air valve 55 in the casing section 12 being open to 65 provide an air cushion in the section 12 to prevent pounding and to effect a proper lift of the water through the pipe 19.

If it is desired to deliver water through 70 the spout 17 or lift the water to the tank (not shown), through the pipe 19 by the power of a wind-mill, the fastenings α are removed from the cross-head so as to permit disconnection of the upper ends of the links 32 and 36 from the cross-head. If desired, 75 the handle 43 may be removed or permitted to remain connected to the arm 41. In any event, the pitman connection 45 is preferably disconnected from the power transmission mechanism D. The wind-mill rod (not 80 shown) is then connected to the apertured extension 39 of the cross-head 37, which, being connected to the piston 16, causes the latter to be reciprocated to effect discharge of the water through the spout 17 or to be 85 lifted up through the pipe 19, according to the manipulation of the valves 18, 21 and 55.

What is claimed is—

1. In a pump, a casing, a support for the casing, a piston rod in the casing, a sleeve 90 mounted on said support and embracing the lower end of the casing and fixed thereto and provided with a lateral projection, a shaft journaled in said projection, arms secured to the shaft, a cross-head secured to 95 the piston rod, relatively long links pivotally connected to said arms and to said cross-head, and a handle secured to said shaft adjacent one of said arms.

2. In a pump, a casing, a support for the 100 casing, a piston rod in the casing, a sleeve mounted on said support and embracing the lower end of the casing and fixed thereto and provided with a lateral projection, a shaft journaled in said projection, a double-armed 105 lever connected to said shaft, another arm connected to said shaft, a cross-head secured to the piston rod, links pivotally connected to said arms and to said cross-head, and means connected to the double armed lever 110 to rock said shaft to reciprocate said links and said piston rod.

In testimony whereof I affix my signature in the presence of two witnesses.

GUSTAV E. HAAR.
